(57) **CLAIM**

The ornamental design for an electronic device, as shown and described.

DESCRIPTION

FIG. 1 is the front/left-side/top perspective view of an electronic device showing our new design;

FIG. 2 is the front elevational view thereof;

FIG. 3 is the rear elevational view thereof;

FIG. 4 is the left-side elevational view thereof;

FIG. 5 is the right-side elevational view thereof;

FIG. 6 is the top-side plan view thereof; and,

FIG. 7 is the bottom-side plan view thereof.

The diagonal shading on the front in FIGS. 1 and 2 indicates the transparency of the front surface. All other surface shading, which is depicted with lighter line weight, indicates the contours of the claimed surfaces.

The broken lines shown in the figures that are immediately adjacent to the shaded areas and define unshaded regions, represent the bounds of the claim, while all other broken lines, including the three tiny circles at the top front near the speaker opening are directed to environment; the broken lines form no part of the claimed design.
